The ornamental design for the protective plastic cover for grater, as shown and described.

DESCRIPTION

FIG. 1 is a perspective view of a protective plastic cover for grater showing one aspect of my new design;

FIG. 2 is a left side view thereof;

FIG. 3 is front view thereof;

FIG. 4 is a top view thereof;

FIG. 5 is rear view thereof;

FIG. 6 is a right side view thereof; and,

FIG. 7 is a sectional view through the central opening.

The broken lines are for illustrative purposes only and form no part of the claimed design.
